UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,321,866.

Specification of Letters Patent. Patented Nov. 18, 1919.

Application filed July 30, 1917. Serial No. 183,587.

To all whom it may concern:

Be it known that I, JESSE G. VINCENT, a citizen of the United States, and resident of Detroit, Wayne county, State of Michigan, have invented certain new and useful improvements in Hydrocarbon-Motors, of which the following is a specification.

This invention relates to the making of motor cylinders and particularly to the forming of cylinder blocks and to connecting various parts of built up cylinders.

One of the objects of the invention is to connect metal parts by a novel method or process.

Another object of the invention is to build up a motor cylinder by a novel method.

Another object of the invention is to provide a novel jacketed cylinder construction of extremely light weight and great strength.

Another object of the invention is to provide a cylinder block made up of several cylinders and connected water jacket.

Other objects of the invention will appear from the following description, taken together with the drawings which form a part of this specification, and in which:

Figure 1 is a side elevation and part vertical section of a block of motor cylinders made according to this invention;

Fig. 2 is a plan view of the block of cylinders shown in Fig. 1, with the cam shaft housing removed therefrom;

Fig. 3 is a side elevation of one of the parts of the sheet metal water jacket used in forming the cylinder block shown in Fig. 1;

Fig. 4 is partly in elevation and partly in vertical transverse section on the line 4-4 of Fig. 2, and illustrates one of the motor cylinders shown in Fig. 1, with a cam shaft housing mounted above it;

Fig. 5 is a transverse section on the line 5-5 of Fig. 3;

Fig. 6 is an underneath view of the lower ends of two of the cylinders one being an inner and the other an outer cylinder of a block;

Fig. 7 is an enlarged sectional view of one of the elbows and adjacent parts of the cylinder and water jacket;

Fig. 8 is a side elevation of the upper part of the cylinder shown in Fig. 7, with parts broken away to show the welded joint;

Fig. 9 is a perspective view of a forging or casting forming a flange piece which is attached to one of the elbows;

55

Fig. 10 is a fragmentary view illustrating the method of forming one of the welded joints between the cylinder and water jacket;

Fig. 11 illustrates the method of forming 60 the welded joint between one of the elbows and the cylinder proper, and

Fig. 12 illustrates a method similar to that shown in Fig. 11.

Referring to the drawings, Figs. 1 and 2 represent a cylinder block B adapted to be used as part of a hydrocarbon motor. As shown, the block is made up of three cylinders indicated at 20, and they are joined together as by welding at their bottom flanges, the welded joints being shown at 21 in Fig. 1. The cylinders are surrounded by a water jacket which is made up of two parts joined together and to the cylinders as will be more fully hereinafter described. 70 One of these water jacket parts 22 is shown in Figs. 3 and 5 and it will be understood that the two parts are identical except that one of them may have tubes 23 secured thereto for the purpose of feeding water to or 80 from the space between the water jacket and the cylinders. By joining these two jacket parts together and to the cylinders all of the parts are thus bound together to make a rigid cylinder block.

85
In Fig. 4 there is illustrated, partly in elevation and partly in section, a complete cylinder built up of various parts in accordance with this invention. This cylinder is of the overhead valve type, and it will 90 be understood that they may be built up separately or in pairs or three in a block as desired for the particular conditions under which they are used. For the purpose of illustrating this invention the cylinder 95 shown in Fig. 4 may be referred to as one of the cylinders of the cylinder block shown in Figs. 1 and 2, and it will be so described.

The cylinder 20 is preferably made of a steel forging machined both inside and outside and formed with a flange 24 at its lower or outer end for the purpose of attaching it to a crank case or to adjacent cylinders, with a combustion space 25 at its upper or inner

end, and with inlet and outlet ports 26 and 27 respectively and spark plug ports 28 communicating with the combustion space. The space 25 is of slightly larger diameter than the bore of the cylinder to permit the use of larger valves, and the cylinder at each of the ports 26 and 27 is extended slightly beyond the port in the form of a tubular part 29 with an internal shoulder 30 spaced from the end of the tubular part and adjacent the valve seat portion 31 of the port.

Elbows or elbow-like parts 32 and 33 are secured to the cylinder proper at the ports 26 and 27 respectively, the part 32 forming the intake passage and the part 33 forming the exhaust passage, for the motor. The only difference between these two elbow-like parts is that the valve stem portion 34 of the elbow 33 is somewhat longer than in the elbow 32 and a depression 35 is formed adjacent this portion so that the cooling water may more readily reach it and thereby keep it cool.

Each of these elbows 32, 33, has a tubular part 36 adapted to fit within the tubular part 29 and have its end abut against the shoulder 30, and an external flange 37 on the elbow is then adjacent the end of the tubular part 29 of its respective port. This arrangement of the tubular part 29 of the cylinder and the tubular part 36 of the elbow is illustrated in Fig. 11 before the welding operation which joins them takes place. As shown therein the flange 37 is slightly tapered so that there is not a close fit between it and the end of the tubular part 29, and for the purpose of making a welded joint between those two parts a piece of wire 38 is placed around the loose joint and a welding heat is applied to the wire and the adjacent parts of the tubes whereby the wire and adjacent parts are fused together. This welded joint is shown particularly in Fig. 7 as well as in Fig. 4.

Fig. 12, shows the same arrangement of tubular parts but in this case the wire 38 is omitted and a welding heat is applied directly to the flange 37 changed slightly from the form shown in Figs. 4, 7 and 11, and the end of the tubular part 29 so that these two parts are directly joined together. The joint is shown in dotted lines at 39.

It will be seen that the two elbows 32 and 33 face oppositely and away from the middle of the cylinder and their valve stem portions 34 extend diagonally upward in the form of bosses 34' on the tops of the main body portions of the elbows. These elbows in effect become part of the cylinder and they are surrounded by the water jacket together with the rest of the cylinder. The water jacket part 22 shown in Figs. 3 and 5 will be seen to have three openings 40, 41 and 42 formed therein and upon reference

to Fig. 4 in particular it will be seen that these openings are respectively for the upwardly projecting boss 34', the projecting end 43 of the elbow, and a boss 44 in which the spark plug port 28 above referred to is formed. The jacket part 22 is secured to these three parts of the cylinder by a novel welding method which will now be described. Since the method of connecting the jacket to each of these three parts is the same, only one connection will be described in detail.

The tubular part 43 of the elbow 32 is shown in section in Figs. 7 and 10. In Fig. 10 it will be seen that this tubular part of the elbow has an external flange 45 machined on it and on the flange is a rim or ring 46 which is substantially the thickness of the sheet metal water jacket to which it is to be connected. This ring 46 is separated from and parallel to the outer wall of the tube and it is so arranged on the flange 45 as to leave part of that flange extending beyond the ring to form a shoulder 47. The water jacket 22 is now placed around the cylinder and the tubular part 43 of the elbow and its ring 46 are inserted through the opening 41 so that the jacket rests against the base of the ring 46 and the shoulder 47 formed by the extended part of the flange 45. A welding heat is now applied to the ring 46 and the adjacent part of the jacket 22 so that these metal parts flow together and form a welded joint. This joint is indicated in dotted lines at 48. Similar joints are made at 49 and 50 as shown in Figs. 4 and 7. Besides thus welding the two water jacket parts 22 to the cylinders, the parts are welded together along the median plane of the cylinder as at 51, Fig. 4, and the lower ends of the jacket parts 105 are secured as by welding, to a downwardly bent flange 52 formed on the cylinder as shown in Fig. 4.

For the purpose of supporting and inclosing the motor cam shaft at the top of the cylinder a cam shaft housing 53 is provided and it is adapted to be supported through its legs 54 upon the elbows 32 and 33 above described. As shown, the means of support is in the form of a ring 55 welded as at 56 or otherwise secured to the projecting part 43 of each of the elbows 32 and 33. The ring 55 is shown in detail in Fig. 9 and it will be seen that a foot 57 extends upwardly therefrom, and as shown in Fig. 4 is positioned to receive one of the legs 54 above referred to. These parts may be secured together by bolts 58. The ring 55 also forms an attaching flange 59 for the headers or manifolds which are adapted to be secured to the elbows.

It will be understood that other forms and modifications may be made without depart-

ing from the spirit or scope of the invention.

Having thus described my invention, what I claim and desire to secure by Letters Patent is:—

1. A method of making a cylinder block for motors consisting in welding the outer ends of a plurality of motor cylinders together, forming sheet metal water jackets in two parts, one part for each side of the several cylinders, and welding said jacket parts to the cylinders and to each other to bind all together in a rigid cylinder block.

2. A method of making a cylinder block for motors consisting in welding the outer ends of a plurality of motor cylinders together, forming sheet metal water jackets in two parts, one part for each side of the several cylinders, and welding said jacket parts to the cylinders at the lower ends of the jackets and at the inlet and outlet openings, and to each other, to bind all together in a rigid cylinder block.

3. A motor cylinder having an outwardly extending cylindrical boss, said boss having an external flange and an integral ring directly on the flange separated from and parallel to the outer wall of the boss leaving part of the flange extending beyond the ring to form a shoulder, said ring being of substantially uniform thickness throughout, and a sheet metal jacket about the cylinder and through which said boss and ring outwardly project so that the jacket rests on said shoulder and against the base of said ring, said jacket being of substantially uniform thickness throughout and of substantially the same thickness as said ring, and a welded joint between said ring and the edge of said jacket immediately adjacent said ring.

4. A motor cylinder having an integral flange and an integral rim on the flange separated from and parallel to the wall of the cylinder leaving part of the flange extending beyond the rim to form a shoulder, and a sheet metal part resting on said shoulder with its edge in contact with the outer surface of the rim, and a welded joint between said rim and the edge of said sheet metal part immediately adjacent thereto.

5. A motor cylinder having an opening and formed at the opening with a shoulder spaced inwardly from the outer end of the opening, a tube inserted in the opening with its end abutting against said shoulder, said tube having a tapered shoulder making a somewhat open joint with the cylinder at the end of said opening, and a weld formed between the cylinder and tube at said end and said tube shoulder.

6. A motor cylinder comprising a cylinder proper, elbows at the inner end thereof facing oppositely and away from the middle of

the cylinder, and a sheet metal water jacket about the cylinder and welded to said elbows.

7. A motor cylinder comprising a cylinder proper, elbows at the inner end thereof for the inlet and exhaust gases, a cam shaft housing, and means for supporting said housing from said elbows.

8. A motor cylinder comprising a cylinder proper, an elbow forming a gas passage at the inner end thereof, a cam shaft housing, and means for supporting the housing on said elbow.

9. A motor cylinder comprising the main cylinder part, an elbow at the end of the main cylinder part, a sheet metal water jacket about the cylinder and connected to said elbow so that the end of the elbow projects through the jacket, a cam shaft housing, and means for supporting said housing from the projecting end of the elbow.

10. A motor cylinder comprising the main cylinder part, elbows at the end of the cylinder facing in opposite directions, a sheet metal water jacket about the cylinder and connected to said elbows so that their ends project through the jacket, and a cam shaft housing supported on the projecting ends of said elbows.

11. A motor cylinder comprising a cylinder proper, an elbow forming a gas passage at the inner end thereof, a sheet metal water jacket about the cylinder and connected to said elbow so that a part thereof projects through the jacket, and a cam shaft housing supported on said projecting part.

12. A motor cylinder having a cylindrical boss, said boss having an external flange and a ring on the flange separated from and parallel to the outer wall of the boss leaving part of the flange extending beyond the ring to form a shoulder, and a sheet metal jacket about the cylinder and through which said boss and ring outwardly project, said jacket resting on said shoulder, and a welded joint between said ring and the adjacent edge of said jacket.

13. A motor cylinder having a cylindrical boss, said boss having an external integral flange and an integral ring on the flange separated from and parallel to the outer wall of the boss leaving part of the flange extending beyond the ring to form a shoulder, and a sheet metal jacket about the cylinder and through which said boss projects, said jacket resting on said shoulder, and a welded joint between said ring and the edge of said jacket immediately adjacent said ring.

14. A motor cylinder having an opening and bored at the opening to form a shoulder spaced inwardly from the outer end of the opening, a tube inserted in the opening with its end abutting against said shoulder, said

tube having a shoulder adjacent the outer end of said opening, and a weld formed between the cylinder and tube at said end and said tube shoulder.

5 15. A motor cylinder having an opening and bored at the opening to form a shoulder spaced inwardly from the outer end of the opening, a tube inserted in the opening with

its end abutting against said shoulder, said tube having an external flange forming a joint with the cylinder at the end of said opening, said flange being welded to the cylinder at said joint. 10

In testimony whereof I affix my signature.

JESSE G. VINCENT.
